JOSEPHUS SMITH TOWNDROW, OF MOLINE, ILLINOIS, ASSIGNOR
TO W. P. HUMPHREY, OF DAVENPORT, IOWA.

Letters Patent No. 83,341, dated October 20, 1868.

IMPROVED POCKET DRINKING-CUP.

The Schedule referred to in these Letters Patent and making part of the same.

To all whom it may concern:

Be it known that I, JOSEPHUS SMITH TOWNDROW, of the town of Moline, in the county of Rock Island, and State of Illinois, have invented a certain new and useful Pocket Drinking-Cup or Goblet; and I do hereby declare that the following is a full, clear, and exact description thereof, reference being had to the accompanying drawings making part of this specification, and to the letters of reference marked thereon, like letters indicating like parts wherever they occur.

To enable others skilled in the art to construct and use my invention, I will proceed to describe it.

In the accompanying drawings—

Figure 1 is a vertical section of the upper part or cup.

Figure 2 is a perspective view of the lower part or stand.

Figure 3 shows the two parts, screwed together, forming a complete cup, ready for use.

Figure 4 shows the same, when reversed and screwed together, for greater convenience in carrying, and the exclusion of dirt.

The cup is represented in section, and the stand in perspective, in each case.

The whole is described as follows: The cup A is made of metal, or of glass, gutta-percha, or other material, but with a thick metallic bottom, with a screw-hole, *a*, in the centre, into which the screw *n*, at top of the stand B, is fitted.

When screwed together, as shown in fig. 3, the hole is stopped water-tight, forming a perfect drinking-cup.

By reversing the position of the cup, inverting it, and screwing the parts together, as shown in fig. 4, it is put in a convenient portable form, and, the parts fitting tightly, all dust is excluded, and the cup kept clean and fit for use.

Having thus described my invention,

What I claim is—

A pocket-goblet, consisting of the cup A and stand B, constructed so that they may be detached, and the cup connected to the stand in a reversed position, substantially as herein described.

JOSEPHUS SMITH TOWNDROW.
